William Clegg, of New Haven, State of Connecticut
Letters Patent.

The schedule referred to in these Letters Patent & making part of the same, containing a description in the words of the said William Clegg, himself of his improvement in the mode of manufacturing Spots or Bobbins.

To all persons to whom these presents shall come.

William Clegg, of New Haven in the County of New Haven in the State of Connecticut, Gentleman sends greeting.

Be it known that I, William Clegg, have invented constructed, made, and apply to use a new and useful improvement, in the mode of manufacturing Spots or Bobbins called Clegg's improved collar barrel spots or Bobbins, specified in the words following.

This improvement in the mode of manufacturing Spots or Bobbins, has the preference over all others heretofore in use because the former mode of making Spots or Bobbins used for manufacturing Cotton has been to make the joint that passes thru the heads the same size or something less than the barrel, the part passing thru the heads being less than the main shaft or barrel by having a small shoulder formed by lessening the diameter of the ends of the barrel, the consequence of this mode of construction is the bobbin are weak and insecure in this part, the heads continually separating from the barrel, this often when the bobbins are locked with cotton, which occasions a loss not only of the spot or bobbin but of the yarn which may be in the bobbins at the time of its failure. The success of other establishments has also been at great expense in repairing bobbins to repair such spots or bobbins which are made with the same defect in them as was when Clegg's

and said cotton board of said bottoms shall have one or
several rows of the said improvement of 161 of cotton or
of bottom and all other manner of, and shall be being
cotton or jute on the board, formed of the same piece of wood
or like wood the board the hole being bored in them same
surface so as to receive the cotton on the ends of the board
is a suitable depth the extreme end of the board being
quite true the board of a size nearly equal to the diameter
of the middle of the board the board or board (as they are
made single or double) secured firmly to the board cotton
with or without Glue, pins, nail, or screw, or with either
of any of these the whole constituting a new and valuable im-
provement in the construction of Spots or bottom and in the
manufacture of cotton and other article & will have a tendency
to save a very great part of the expense hitherto incurred
by cotton manufacturers for the article of Spots & Bottoms

In testimony that the above is a true
specification of my said improvement, as above described
I have hereunto set my hand and seal the 9th day of January
in the year of our Lord 1830.

Witness,

Edward Catherpey

John Hayes

William Clegg
